UNITED STATES PATENT OFFICE.

FRED EVANS AND JOSEPH CORCOS, OF NEW YORK, N. Y., ASSIGNEES TO SAID CORCOS.

DESIGN FOR A RECORD-RECEIVING CARD OR ARTICLE OF SIMILAR NATURE.

54,610.

Specification for Design.

Patented Mar. 9, 1920.

Application filed August 4, 1919. Serial No. 315,320. Term of patent 14 years.

To all whom it may concern:

Be it known that we, FRED EVANS and JOSEPH CORCOS, both residing in New York, county and State of New York, (whose post-office addresses, respectively, are 51 East 42nd street, New York city, and 59 Pearl street, New York city,) have invented a certain new, original, and ornamental Design for a Record-Receiving Card or Article of Similar Nature, of which the following is a specification, reference being had to the accompanying drawing, forming part thereof.

The figure is a face view of a record receiving card, showing our new design.

We claim:

The ornamental design for a record receiving card or article of similar nature, as shown.

FRED EVANS.
JOSEPH CORCOS.
